HAND PIECE FOR A COMBINED SKIN STIMULATING AND CLEANING DEVICE

Medard W. Welch, 1111 Sheridan Road,
Winnetka, Ill. 60093

Filed Jan. 20, 1971, Ser. No. 108,253

Term of patent 14 years

Int. Cl. D24—05, 99
U.S. Cl. D83—1

Fig. 1.

Fig. 2.

Fig. 3.

Fig. 5.

Fig. 4.

FIG. 1 is a side elevational view of a hand piece for a combined skin stimulating and cleaning device, showing my new design;

FIG. 2 is a top plan view thereof;

FIG. 3 is a bottom plan view thereof;

FIG. 4 is a left end elevational view thereof; and

FIG. 5 is a right end elevational view thereof.

I claim:

The ornamental design for a hand piece for a combined skin stimulating and cleaning device, as shown.
